UNITED STATES PATENT OFFICE.

JAMES A. SUMNER AND ZIGLER HOENSTINE, OF LOUISVILLE, NEBRASKA

DESIGN FOR A TRACE-CARRIER.

SPECIFICATION forming part of Design No. 32,996, dated July 24, 1900.

Application filed April 19, 1900. Serial No. 13,546. Term of patent 7 years.

To all whom it may concern:

Be it known that we, JAMES A. SUMNER and ZIGLER HOENSTINE, citizens of the United States, residing at Louisville, in the county of Cass and State of Nebraska, have invented and produced a certain new and original Design for Trace-Carriers; and we do declare the following to be a full, clear, and exact description of the invention, such as will enable others skilled in the art to which it appertains to make and use the same.

The invention relates to a new and original design for a trace-carrier; and it consists of a design of the shape and configuration shown in the accompanying drawings, in which—

Figure 1 is a plan view. Fig. 2 is a side view, and Fig. 3 is an end view.

The design comprises a base-plate 1, formed with a central longitudinal slot or opening *a*, having its side walls *a'* curved regularly in the arc of a circle in an outward direction from a central point, the corresponding arc-shaped portions of the two side walls being arranged to face each other, as shown. This slot or opening is bounded by the sides 2 and 3 and ends 4 and 5 of the plate, which are flat and formed with longitudinal slots *b*, all independent of the said longitudinal slot *a*. The end 4 is in the form of a flat plate or extension, and the slot therein is located at or about the center thereof. Projecting upwardly from the sides 2 and 3 are vertical elliptical-shaped lugs 6, provided at their upper ends with horizontal ear-shaped heads 7, which cover said lugs and whose upper surfaces are flat or plane-surfaced and lie in the

same horizontal plane. The convex sides of these heads 7 face outwardly, while the concaved sides thereof face inwardly and correspond to the curvature of the side walls *a'*. 40 The butt or wide curved or rounded ends of the heads also face the end 4 of the plate, and the tapered inwardly-projecting point ends thereof face the end 5 of the plate. The flat end 4 is joined to the plate 1 by a transversely-extending V-shaped arch-bar 8, which curves outwardly and laterally from its vertex or central point and is formed with straight and vertical pendent legs *c*. To this central point is connected a longitudinally- 50 extending arch-bar 9, having a central curved portion and a straight and vertical leg *d*, rising from the end 5, in rear of the long and narrow longitudinal slot *b* therein.

The particular shape and configuration of 55 the parts 1, 6, 7, and 8 constitute the essential features of the design and impart to the same a peculiar and distinctive form and appearance.

Having thus described our invention, what 60 we claim is—

The design for a trace-carrier, as herein shown and described.

In testimony whereof we have hereunto set our hands in presence of two subscribing witnesses. 65

JAMES A. SUMNER.
ZIGLER HOENSTINE.
